UNITED STATES PATENT OFFICE

122,634

DESIGN FOR AN ELECTRIC STEAMING IRON

Henry V. Ekstedt, St. Louis, Mo., assignor to
Ernest F. Pohl, St. Louis, Mo.

Application July 26, 1939, Serial No. 86,261

Term of patent 14 years

To all whom it may concern:

Be it known that I, Henry V. Ekstedt, a citizen of the United States, residing in the city of St. Louis and State of Missouri, have invented a new, original, and ornamental Design for an Electric Steaming Iron, of which the following is a specification, reference being had to the accompanying drawing, forming part thereof.

In the drawing:

Fig. 1 is a perspective view of an electric steaming iron, the same being inverted and showing my new design of pressing surface.

Fig. 2 is a plan view of the pressing surface of the electric steaming iron.

In Fig. 1 of the drawing the bottom and one side of the electric iron are illustrated. The

other side of the electric steaming iron is substantially the same as the side shown in Fig. 1.

The characteristic features of the steaming iron of the design shown reside in the relatively small circular recess comprising frustoconical side walls and a flat surface elevated above and parallel with the plane of the pressing surface of the iron, said recess being located near the front end of the pressing surface and having formed in its flat surface a circular series of ports arranged concentrically with the circular outline of the recess.

I claim:

The ornamental design for an electric steaming iron, as shown and described.

HENRY V. EKSTEDT.
